UNITED STATES PATENT OFFICE.

SUGAJI SUZUKI, OF OGDEN, UTAH.

SHIP-FLOATING DEVICE.

1,233,141.

Specification of Letters Patent. Patented July 10, 1917.

Application filed January 31, 1917. Serial No. 145,619.

To all whom it may concern:

Be it known that I, SUGAJI SUZUKI, a citizen of the Empire of Japan, and a resident of Ogden, in the county of Weber and State of Utah, have invented a new and Improved Ship-Floating Device, of which the following is a full, clear, and exact description.

My invention has for its object to provide a novel means for connecting inflatable bags around a ship or other object, for raising the ship or other object. Fastening means are provided which prevent water from passing between the bags, and there are also means which permit of the inflation of the bags with air or some other fluid.

Additional objects of the invention will appear in the following specification in which the preferred form of the invention is disclosed.

In the drawings similar reference characters denote similar parts in all the views, in which—

Figure 1 is a view showing in elevation a ship around the bow of which my device is secured;

Fig. 2 is a sectional view on the line 2—2 of Fig. 1;

Fig. 3 is a view showing one of the inflatable bags with a part broken away to illustrate the construction;

Fig. 4 is a sectional view on the line 4—4 of Fig. 3;

Fig. 5 is an enlarged sectional view on the line 5—5 of Fig. 3;

Fig. 6 is a fragmentary view illustrating a portion of one of the outer bags;

Fig. 7 is a sectional view on the line 7—7 of Fig. 6;

Fig. 8 is a view illustrating the clamping means, U-shaped in cross-section, for securing the adjacent sides of neighboring bags together;

Fig. 9 is a sectional view on the line 9—9 of Fig. 8; and

Fig. 10 is a sectional view illustrating a modified form of the invention.

By referring to the drawings, it will be seen that a plurality of bags 15 are provided, 50 stiffening plates 16 being disposed at the middle portions of the sides of the bags 15, and bolts 17 being disposed through the stiffening plates 16 and the sides of the bags 15 for securing the stiffening plates 16 against the sides of the bags 15 and the sides of the bags 15 in contact with each

other. Bolts 18 are also disposed through the stiffening plates 16 and the sides of the bags 15. Rings 19 or hooks 20 are articulated to the ends of the bolts 18 to assist 60 in securing the bags 15 to the sides of a ship 21. The ends of the stiffening plates 16 are curved at 22 so that they will press the sides of the bag 15 at those points against vertically extending pipes 23 which 65 lead to the bag 15 above and below the stiffening plates 16. The pipe 23 has a branch 24 which extends through an opening 25 in one of the stiffening plates 16, the branch 24 having an elbow 26 at which there 70 is a valve having a winged operating member 27. A collar 28 is disposed on a pipe 29 beyond the valve, this collar 28 having arms 30 spaced apart for embracing the winged member 27, for holding the winged 75 member 27 in open or closed position. The pipe 29 is connected with a similar pipe on an adjacent bag, so that the air will pass from one bag to the other bags, it being sufficient if air or other fluid is admitted 80 into one or two of the bags, for this air or other fluid will pass from the said bag or bags to the remaining bags.

Stiffening members 31 are disposed between the curved ends 22 of the stiffening 85 plates 16 and the sides of the bag 15 at that point, the bolts 17 passing through the stiffening members 31 for holding the said stiffening members in position.

The bags 15 are preferably disposed at 90 each side of the ship, and the bottoms of these bags 15 are secured together by U-shaped members 32, between the sides 33 and 34 of which the adjacent edges of neighboring bags are disposed, there being 95 a threaded orifice 35 in the side 33 of the U-shaped member 32 in which a screw 36 is disposed, this screw 36 serving to move a clamping member 37 against the edges of the bags to press the edges of the bags 100 against the sides 34 of the U-shaped members 32. In a similar manner the vertical edges of the bags 15 are secured together by means of the U-shaped members 32, one of the U-shaped members 32 serving to connect 105 an edge of the forward bag 15 at one side of the ship with an edge of the forward bag 15 at the other side of the ship. As has been stated, the interior of each bag is connected with the interior of the neighboring bags by means of the pipes, the valves commanding the communications being open 110

when the bags are in use. The bags 15 are secured to longitudinally extending chains 38 at the sides of the ship by means of the hooks 20, the chains 38 being held in desired positions by means of vertically extending chains 39. To the rings 19 there may be secured additional bags 40 which are illustrated in Figs. 2, 6 and 7 of the drawings, the bottoms of these bags 40 being secured together by stiffening plates 41 and bolts 42. Pipes 43 enter the bags 40, the pipes 43 being connected by valves having winged operating members 44, it being possible to connect pipes 45 extending from the valves, with similar pipes on neighboring bags 40 so that air will pass from one bag to another and to connect some of the pipes 45 with the pipes 29 so that the bags 40 may be inflated from the bags 15. In addition to the bolts 42, bolts 46 are disposed through the stiffening plates 41 and the sides of the bags 40, the said bolts having rings or hooks 47 at their ends, by which means they may be connected with the hooks 20 or the rings 19 on the bolts 18.

As will be seen by referring to Fig. 10 of the drawings, it is possible to introduce framing or extension members 48 between the sides of the ship and the bags 15 so that repairs may be made.

Having thus described my invention, I claim as new, and desire to secure by Letters Patent:

1. In a ship floating device, a plurality of 35 inflatable bags having edges, a member U-shaped in cross-section disposed through adjacent edges of neighboring bags, and a clamp on one side of the U-shaped member for pressing the adjacent edges of the neighboring bags in the direction of the other side of the U-shaped member.

2. In a ship floating device, a plurality of 40 inflatable bags having edges, and clamping means for securing together the adjacent edges of neighboring bags.

3. In a ship floating device, a plurality of 45 inflatable bags disposed side by side, clamping means for securing together the adjacent edges of neighboring bags, a pipe extending from the interior of each bag, and means for connecting the pipes.

4. In a ship floating device, a plurality of 50 inflatable bags disposed side by side, clamping means for securing together the adjacent

edges of neighboring bags, a pipe extending 55 from the interior of each bag, a stop having an operating wing for each pipe, a sleeve 60 slideable on each pipe and having arms for embracing the operating wings, and means for connecting the pipes.

5. In a ship floating device, a plurality of 65 inflatable bags, fastening means on the bags by which the latter may be secured to a chain on the ship, and clamping members U-shaped in cross-section for securing together 70 the adjacent edges of neighboring bags.

6. In a ship floating device, a plurality of 75 inflatable bags which are adapted to be disposed some at one side of the ship and the remainder at the other side of the ship, 80 clamping means for securing the bottoms of the bags at one side of the ship with the bottoms of the bags at the other side of the ship, and clamping means for securing together the adjacent vertical edges of neighboring bags.

7. In a ship floating device, a plurality of 85 inflatable bags which are adapted to be disposed some at one side of the ship and the remainder at the other side of the ship, 90 clamping means for securing the bottoms of the bags at one side of the ship with the bottoms of the bags at the other side of the ship, clamping means for securing together the adjacent vertical edges of neighboring bags, a pipe extending from the interior of 95 each bag, and means for connecting the pipes.

8. In a ship floating device, a plurality of 100 inflatable bags which are adapted to be disposed some at one side of the ship and the remainder at the other side of the ship, clamping means for securing the bottoms of the bags at one side of the ship with the bottoms of the bags at the other side of the ship, clamping means for securing together the adjacent vertical edges of neighboring bags, and a frame for holding the bags spaced from the ship to permit of making 105 repairs.

9. In a ship floating device, an inflatable bag, two stiffening plates one disposed at each side of the bag, bolts disposed through the bag and the stiffening plates and provided with fastening rings, and a pipe extending into the bag by which it may be inflated.

SUGAJI SUZUKI.
